UNITED STATES PATENT OFFICE.

LOUIS JANSON, OF BROOKLYN, NEW YORK.

MACHINE FOR INSERTING DIAGONAL STRANDS IN WOVEN-CANE FABRICS.

SPECIFICATION forming part of Letters Patent No. 745,062, dated November 24, 1903.

Application filed September 19, 1902. Serial No. 124,001. (No model.)

To all whom it may concern:

Be it known that I, LOUIS JANSON, a citizen of the United States, and a resident of the city of New York, borough of Brooklyn, in the county of Kings and State of New York, have invented a new and Improved Machine for Inserting Diagonal Strands in Woven-Cane Fabrics, of which the following is a full, clear, and exact description.

My invention relates to that class of machines adapted to insert diagonal strands in woven-cane fabrics; and the purpose of the invention is to so construct the machine that it will be simple, durable, and effective in operation and capable of being operated manually or by power, and, furthermore, to provide a machine in which a rotary depressing device is mounted to travel over the cane fabric, depressing the warp-strands at each side of the weft-strands, and to so reciprocate a needle adapted to carry the diagonal strands that the said needle will move concerted with the depressing device, passing over the depressed warp-strands and under the adjacent weft-strands.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a side elevation of the machine. Fig. 2 is a plan view of the same. Fig. 3 is a longitudinal section through the bed of the machine, taken practically on the line 3 3 of Fig. 2, in which the parts are shown in normal position or in position to start. Fig. 4 is substantially a similar view, but the needle is shown at the end of its receiving stroke, being in position to receive the diagonal strand. Fig. 5 is a transverse section through the bed of the machine, taken practically on the line 5 5 of Fig. 2, the rotary depressing device being shown up or in idle position. Fig. 6 is a section taken on the same line as the section in Fig. 5, but showing the rotary depressing device in lower and operative position. Fig. 7 is a plan view of the guide-bar for the needle and the rotary depressing de-

vice. Fig. 8 is a side view of the forward end portion of the guide-bar shown in Fig. 7. Fig. 9 is a longitudinal section through a portion of the guide-bar and a side elevation of the depressing-wheel operating thereon, a section through the cane fabric and a side elevation of a portion of the needle, illustrating the position of the needle with respect to the depressing-wheel when the latter is operating on the fabric to form a passage for the needle while traveling to a position to receive a diagonal strand. Fig. 9^a is a view similar to Fig. 9, but showing the position of the needle with reference to the depressing-wheel while the needle is carrying the diagonal strand through the cane fabric. Fig. 10 is a detail plan view of a portion of the needle-guide bar and cane fabric thereon, the eye portion of the needle in the position it occupies after having drawn a diagonal strand through the fabric, and a plan view of the gripping device for the delivered end of the diagonal strand to permit the separation of the needle from the strand. Fig. 11 is an enlarged transverse section through an extension from the bed, illustrating in detail the threading mechanism for the needle, the section being practically on the line 11 11 of Fig. 12, the guide portion of the threading mechanism showing in side elevation. Fig. 12 is a longitudinal section through the needle-threading mechanism, which section is taken practically on the line 12 12 of Fig. 11. Fig. 13 is a section through the tracks between which the needle passes, a side elevation of the supporting or carrier block for the needle, and a transverse section through the needle, the section being taken practically on the line 13 13 of Fig. 3. Fig. 14 is a section taken practically on the line 14 14 of Fig. 13. Fig. 15 is a side elevation of the cam forming a portion of the power-driving mechanism of the machine. Fig. 16 is a longitudinal central section through the bed of the machine, illustrating a slight modification in the formation of the rotary depressing devices or mechanism. Fig. 17 is a perspective view of the wheel employed for depressing the cane fabric to receive the diagonal strands. Fig. 18 is a detail view illustrating the construction of the eye of the needle, and Fig. 19 is a detail

view of mechanism acting in conjunction with the needle when it is about to be withdrawn from the diagonal strand it carries.

A represents a pillar or post upon which a base A' is supported, and the said base preferably consists of upwardly and outwardly flaring side and end sections, as is shown in Figs. 1 and 2, and outwardly-extending horizontal upper marginal flanges 10. At one end of the base on the end flange the trunnions of a roller 11 are journaled in suitable bearings 12, and from the same flange downwardly and outwardly extending hangers 13 are carried, in which hangers a drum 14 is removable, adapted to carry the woven cane A², through which the diagonal strand is to be passed. Preferably at the lower end of each hanger 13 a horizontal slot 15 is formed to receive the trunnions of the drum 14, and pins 16 normally close the said slots, as is shown in Fig. 1. On one trunnion of the said drum 14 a crank-handle 17 is secured to facilitate the operation of the drum. At the opposite end of the base and upon the end flange 10 a second roller 18 is journaled in suitable bearings 19, and from this latter end of the base hangers 20 are projected downward, having slots 21 produced therein to receive the trunnions of a drum 23, the slots 21 being normally closed by pins 22 or their equivalents. The woven cane A² is passed from the drum 14 to the drum 23, or vice versa, and a trunnion of the drum 23 is provided with a suitable crank-hanger 24, as is shown in Fig. 2.

A drive-shaft 25 is passed diagonally through the pillar or post A, as is indicated by dotted lines in Fig. 2, and at one end of this shaft 25 a driving-pulley 26 is located, while at the opposite end of the shaft a bevel-gear 27 is secured, adapted to mesh with a similar gear 28 on a short horizontal shaft 29, journaled in suitable bearings extended from the said post A, as is shown in Fig. 1. An arm 30 is pivotally mounted on the shaft 29, and the said arm 30 is provided with a roller 33, which roller travels in a race 32, formed in one side of a heart-shaped cam 31, (illustrated particularly in Fig. 15,) which cam is secured upon one end of the shaft 29, as is shown in Figs. 1 and 2. The arm 30 is pivotally attached to a lever-arm 34, the said lever-arm being suitably pivoted in bearings 35 on the support for the machine or on a projection from the lower portion of the supporting post or pillar A of the machine.

The bed or operative section of the machine extends diagonally of the base A', as is shown particularly in Fig. 2, and the said bed in its entirety is designated by the reference-letter C. This bed C is supported by brackets D and D', located on the side flanges 10 of the base A' near diagonally opposite ends of the base, and these brackets D and D' will be hereinafter fully described. From the bracket D' track-bars E are projected horizontally in parallel lines, a cross-section of

which track-bars is fully shown in Fig. 13. These track-bars are connected at their inner ends by, preferably, an angular cross-bar 70 e, which is secured to the bracket D' and to the base A'. Each track E is provided with a T-head 36, as is best shown in Fig. 13, whereby longitudinal upper ribs are formed on each track. On the said inner ribs formed by the T-heads 36 carrier or supporting blocks are mounted to slide, the said carrier-blocks consisting, preferably, of a substantially U-shaped body 37, having side members or plates 40, as is shown best in Fig. 14, and these side plates 40 carry upper rollers 38 and lower rollers 39. The upper rollers 38 engage with the upper surfaces of the inner ribs of the tracks E and the lower rollers 39 with the under surfaces of the said ribs. Preferably each carrier or supporting block 37 is provided with a sleeve 41, fixed to its body portion and extending longitudinally of the bed C of the machine, as is particularly shown in Fig. 14. Within each sleeve 41 a tubular section 42, of rubber, leather, or other elastic material, is located, and through the said tubular sections 42 the shank of the needle 43 of the machine is passed, which needle is adapted to draw the diagonal strand 95 through the woven cane.

The carrier or supporting blocks 37 are adapted to support the needle between its ends when the needle is in its normal position, as is shown in Fig. 3; but when the needle is in position to receive a diagonal strand, as is shown in Fig. 4, the carrier or supporting blocks 37 are brought close together in any suitable or approved manner, spreading out again in any suitable way—as, for example, through the medium of pins of different lengths extending from the inner faces of the tracks E, so as to permit sundry of the blocks to pass, while others will be held stationary in position to support the needle when it is carried outward or travels in a direction to draw a diagonal strand through the fabric. The blocks are brought to their assembled position (shown in Fig. 4) through the medium of a carriage F, which is preferably rectangular, as is shown in Fig. 2, and is adapted to travel and be guided upon the upper portions of the tracks E.

It may here be remarked that set-screws 42^a are employed in connection with the supporting or carrier blocks 37 to cause the flexible or yielding inner sleeves 42 to have sufficient bearing at all times on the needle 43 to enable the needle in its forward or rearward movement to bring about a similar movement on the part of the said bearing-blocks.

The carriage F is provided with an opening 44^a therein, the length of which opening regulates the distance the needle shall move at its point to and from the rotary depressing devices, to be hereinafter described, as the point of the needle assumes one position relative to such devices when the needle is being carried to a position to receive a diagonal strand, as

48 from the upper movable section 47 of each bracket D and D' horizontal bars 69 are carried from one bracket to the other in parallel lines, and each side bar 69 for each upper 5 section 47 of a bracket is provided with a longitudinal guide-slot 70, and said slots at what may be termed the "rear" end portions of the side plates 69 are upwardly curved, as is illustrated at 71 in Figs. 3 and 4, for the 10 purpose of carrying a depressing-wheel H, to be hereinafter described, in an upward direction when the sections of the brackets D and D' are brought together, so that the said wheel H will not be in the way when the needle 15 is to be threaded with a strand to be carried diagonally through the fabric.

At the lower portion of each side plate 69 angular additional side plates 72 are secured, as is shown in Figs. 5 and 6, and in the bottom 20 portions of these additional side plates 72 recesses 73 are made, which receive the projections 62 on the needle-guide bar G when the sections of the brackets D and D' are brought together for the purpose of passing 25 a diagonal strand through the fabric held between them.

The depressing-wheel H, above referred to, is provided with trunnions 74, which travel 30 in the slots 70, and these trunnions 74 are journaled in the end portions of links 75, carried in parallelism to a pivotal engagement with a post 76, which extends upward from the inner end of the carriage F, as is shown in Figs. 3 and 4, so that the depressing-wheel H is given 35 movement through the movement of the carriage F, and the carriage is not given movement until the cross-head 44 engages with one or the other of its end walls. The depressing-wheel H is provided with projections 77, 40 arranged in transverse pairs, so as to form a central circumferential channel between the said projections, and the position of the wheel H is such that the channel thus formed is immediately over the longitudinal channel 64 45 in the guide-bar G for the needle, so that the needle will not be interrupted in its passage through the fabric on account of the action of the wheel on the fabric, which wheel H through the medium of its lug 77 as it is moved 50 over the fabric depresses the warp-strands X of the fabric, permitting the needle, which closely follows said wheel and whose eye is immediately below the vertical center of the wheel, as is illustrated in Fig. 9, to pass over 55 the depressed strands X and under the adjacent weft-strands X', and in this manner as the wheel H moves in one direction the needle quickly follows it, and the needle is practically diagonally woven in the fabric and 60 will at its return movement draw the strand diagonally through the fabric as the needle recedes therefrom. The position of the needle and diagonal strand with reference to the warp and weft strands is clearly shown in 65 Fig. 10.

Preferably in the construction of the depressing-wheel H recesses 78 are produced in

the side edges between the projections 77, so that the said wheel will not interfere with the projections 62 upon the needle-guide bar G. 70 Diagonal guideways or depressions 78^a are formed between the projections 77, as is illustrated in Fig. 17, so that the depressing-wheel may better adapt itself to the strands of the cane fabric over which it is to pass; but such 75 guideways or depressions are not absolutely necessary and may be dispensed with, if desired.

Direct motion is imparted to the wheel H through the medium of a rack-bar 79, secured 80 to the inner face of one of the side bars 69, and a gear 80 is located at one side of the supporting-arm 75 for the wheel H adjacent to the said rack, the said gear 80 being mounted upon a suitable stud 81. At the opposite side of the said arm 75 a pinion 82 is carried by the said stud. The gear 80 engages with the rack 79, while the pinion 82 engages with a gear 83, which is fast upon one side of the wheel H, as is best shown in 90 Figs. 5 and 6. In this manner it will be observed that through the rack and gear 79 and 80 rotary motion is communicated to the wheel H by the pinion 82, operated from the gear 80 and the gear 83 on the said wheel. 95

The upper and lower portions of the bed C of the machine are moved to and from each other by a foot-treadle 84 at one side of the supporting-pillar A, which treadle is secured upon a shaft 84^a, mounted to turn in the said 100 pillar-support, and at the opposite side of the pillar-support a crank-arm 85 is secured.

At the inner end of the foot-treadle 84 one end of a connecting-rod 86 is pivoted, the other end being pivotally attached to a lever 105 87, fulcrumed upon a post 88, extending down from the flange 10 of the base, and the lever 87 is also connected with one of the shafts 49 on the upper section of the bed, while upon the opposite side of the pillar A the 110 connecting-rod 86 is duplicated and the lever 87, the latter being attached to the opposite shaft 49, while the connecting-rod is connected with the crank-arm 85, and a spring 89 is attached to the crank-arm 85 and to the 115 base A, acting to normally hold the two sections of the bed separated.

The threading mechanism for the needle 43 is as follows: At the outer side of the lower fixed section 46 of the bracket D an angular 120 table 90 is secured, consisting of a horizontal and a vertical member, as is particularly shown in Fig. 3, 4, 11, and 12, having a slot 91 produced continuously in both of its members. A buffer-block 93 is secured upon the 125 upper face of the horizontal member of the table 90, as is particularly shown in Fig. 12, and this buffer-block at its inner end is provided with a recess 92, which receives the point of the needle 43 when the needle is 130 carried to the end of its rearward stroke to receive a strand to be carried diagonally through the fabric on the machine. At the bottom portion of the horizontal member of

is shown in Fig. 9, and another position when the needle has received a strand and is carrying it through the fabric, as is shown in Fig. 9^a.

5 In the opening 44^a of the carriage F a cross-head 44 is adapted to slide in suitable bearings, as is shown in Figs. 2 and 3, and in this cross-head the outer end of the needle 43 is secured in any suitable or approved manner, 10 the head 43^a of the needle being at its inner end. Motion is imparted to the carriage F when the cross-head 44 has engaged with the inner end of the carriage by means of a link connection 45 with a post 45^a, extending downward from the cross head, the said link 45 being pivotally attached to the lever-arm 34, as is particularly shown in Fig. 1, so that the driving mechanism heretofore described operates directly upon the cross-head and 15 through the cross-head upon the carriage F; but it will be understood that the cross-head 44 may be so formed that it may be manually operated, if so desired.

The brackets D and D' heretofore referred 20 to are alike in construction, and each consists of a lower section 46 and an upper section 47. The lower sections 46 of the brackets D and D' are securely and diagonally attached to the side flanges 10 by bolts or their 25 equivalents, while the upper sections 47 are movable to and from the lower sections 46. Each upper section of a bracket is provided with an inverted-U-shaped section 48. (Shown best in Figs. 5 and 6.)

30 35 The body portion of the upper section 47 of each bracket D and D' is secured to a pin or vertical shaft 49, the said shafts being at opposite sides of the bed C, as is shown in Fig. 2. The upper sections 47 of the brackets D and D' are usually attached to their shafts 49 by means of upper and lower nuts 50 and 51, secured to the said shafts, as is also shown in Figs. 5 and 6. At the upper end of each shaft 49 an arm 52 is secured to the upper 40 surface of the upper or movable section 47 of each bracket, preferably by means of the upper nuts 50 on the shaft 49, and these arms 52, as is shown in Figs. 2 and 5 and in Fig. 6, extend in the direction of the bed C, and 45 at their lower ends carry horizontal extensions 53, and said extensions 53 support horizontal plates 54, vertically located in parallelism at suitable distances apart, as is especially shown in Figs. 5 and 6, one vertical guide-plate 54 being supported by each vertical 50 arm 52.

55 Preferably the opposing guide-plates 54 are connected at their end portions by lower cross-bars 55, and from these cross-bars 55 arms 60 56 extend to one side of the bed. Each arm 56 is of angular construction, being provided with an upwardly-extending member 56^a. These arms 56 are adjacent to posts 57, which 65 extend upward from the flanges 10 of the base A' and carry pointed projections 58 at their upper ends, adapted to enter apertures 60 in horizontal extensions 59 from the U-shaped

portions 48 of the upper bracket-sections 47, as is shown also in Figs. 2, 5, and 6, so as to guide the upper sections of the brackets D and D' in the closing movements of their upper sections over the fixed lower sections 46. Incidentally the projections 58 likewise serve to hold in position the cane fabric between the two sections of the bracket, and when 70 the upper sections 47 of the brackets D and D' are carried upward the vertical extensions 56^a from the angular arms 56 will likewise be carried upward and will serve to disengage the fabric from the projections 48. The plates 80 54 will perform the same function as the sections 47 of the brackets are carried upward, serving at this time to disengage the fabric from the projection from a guide-bar G, to be hereinafter described, and through which the 85 needle is passed which carries the diagonal strand.

It may here be remarked that preferably each shaft 49 is provided with a shoulder 50, (shown in Fig. 6,) which limits the upward 90 movement of said shafts.

In the upper edge of each lower fixed section 46 of each bracket D and D' an opening 61 is produced, narrower at its bottom than at its top. Vertical bars 68 are supported by 95 the bottom walls of the openings 61 in the fixed bracket-sections 46, the bars 68 extending from one bracket-section 46 to the other, and these vertical bars 68 act as supports for the guide-bar G, heretofore referred to. 100

The guide-bar G is shown in detail in Fig. 7 and is provided with projections 62 from its upper face, the projections being preferably arranged in parallel lines near each longitudinal edge of the bar, and between the 105 rows of projections 62 diagonal recesses 63 are produced in the upper face of the bar G, preferably the same distance apart one from the other, and a central longitudinal recess 64 crosses all of the diagonal recesses 63 and 110 extends from one end of the guide-bar G to the other. The projections 62 from the guide-bar G are adapted to enter the spaces formed in the weaving of cane in the usual open manner, and the diagonal recesses 63 are adapted 115 to receive projections from a depressing-wheel acting on the fabric held between the sections of the brackets D and D' to depress the warp-strands, so that the needle in passing through the central channel or recess 64 will pass over 120 the depressed warp-strands and under the adjacent weft-strands.

At the outer end of the needle-guide bar G a recess 65 is made in one side, and at the junction of the walls of the recess 65 a curved 125 or rounded surface 66 is formed over which the eye of the needle passes when the needle is carried toward the bar G, and the said surface 66 serves to guide the needle to the recess or channel 64. At one side of the recess 130 65 a vertical anvil-block 67 is formed for a purpose to be hereinafter particularly described.

At each inner side wall of each projection

the said table 90 one end of a spring 94 is secured, and the opposite end 95 of the said spring is curved upward and is made to bear upon the under side of the shank of the needle 43, as is shown also in Fig. 12, for the purpose of supporting said shank of the needle, and the upper end 95 of this spring is immediately below a guide member 96, beneath which the needle passes. This guide member is located a suitable distance below the upper surface of the horizontal member of the table 90, as is also shown in Fig. 12, and at its outer portion is given a decidedly upward curve. The said upwardly-curved outer portion of the upper guide 96 extends over the recessed end of the buffer 93. This guide 96 is secured to a block 97, which in its turn is attached to the horizontal member of the table 90, and adjacent to the curved surface of the guide extension 96 from the said block 97 a pawl 98 is pivoted, which pawl adjacent to the guide 96 is downwardly inclined. The inclination of the pawl 98 is such that it is directed to the point of the needle when the said point of the needle is in position of rest at the end of its rearward stroke, as is shown in Fig. 11. The pawl 98 is held in its normal position relative to the guide member 96 by means of a spring 99, (shown best in Fig. 2,) which spring is suitably applied, and in the surface of the pawl 98 which is opposed to the guide extension 96 from the block 97 a channel 100 is made. This channel receives the strand 101, which is to be delivered to the needle 43 and is to be a diagonal strand in the fabric, and directs the said strand through the eye of the needle. After passing through the eye of the needle the strand is prevented from passing too far downward by engagement with a stirrup 102, secured to the under face of the horizontal member of the table 90, as is shown in Fig. 11, so that when the needle is drawn backward to carry the strand diagonally through the fabric the strand 101 to be thus carried is bent over at the point of the needle, as is shown in Fig. 10, and said strand is gently drawn through the space between the guide 96 and the pawl 98 as the needle makes its return movement. Under this construction it is evident that the needle may be quickly threaded, and the operator is assured that the strand for threading the needle is properly passed through the eye of the same.

It may be here remarked that the forward wall of the eye of the needle is made more or less sharp for a purpose to be hereinafter described, and this sharpness of the forward wall of the eye of the needle does not act detrimentally on the strand passed through the eye of said needle as the strand is being drawn through the fabric, as at such time little or no resistance is offered to the passage of the strand. After the needle has carried the strand through the fabric the needle is released from the fabric, preferably in the following manner and as is best illustrated in

Figs. 2, 3, and 10: A spring-controlled bolt 103 is mounted to slide in suitable bearings 104, located upon the upper portion of the lower convexed section 46 of the bracket D', and the head of said spring-controlled bolt 103 is directly opposite the anvil 66 of the guide-bar G for the needle. A member of an elbow-lever 105 engages with the outer end 75 of the bolt 103, the said lever being pivoted upon a suitable support upon the aforesaid bracket D', and to the other member of the said elbow-lever 105 a rod 106 is pivotally attached. This rod, as is particularly shown 80 in Fig. 2, extends in direction of the outer end of the track-section of the bed outside of one of the said tracks E, and at the outer end of the said rod 106 a link 107 is pivotally attached, said link being likewise pivotally 85 attached to the inner surface of the track E, adjacent to the outer face of which the rod 106 passes. This link 107 is provided at its outer edge with a pivoted dog 108, the upper end of which dog extends upward, so as to 90 be in the path of the carriage F, as is shown in dotted lines in Fig. 3, and the said carriage at that side where the dog 108 is located is provided with a downwardly-extending spur or lug 109, as is also best shown in Fig. 3. 95 When the needle has drawn the strand 101 through the fabric, as is shown in Fig. 10, the carriage F will have reached such an outer position as to engage with the upwardly-projecting portion of the dog 108, pressing 100 the lower portion of the dog against the link 107 and compelling the upper portion of the link to move outward, and consequently draw the rod 106 in the same direction, which action on the part of the rod 106 causes the 105 elbow-lever 105 to press the spring-controlled bolt 103 inward in direction of the anvil 66 to clamp the delivered end of the strand 101 between the bolt and the anvil. The carriage F has still further outward movement, and in 110 effecting this further outward movement the needle is drawn outward, and the sharp wall of its eye, heretofore mentioned, will cause the delivered end of the strand to be severed, as the strand is firmly held at such time in the 115 manner stated. As the carriage F completes its rearward movement the lug 109 slips over the dog 108, permitting the rod 106 to move inward and causing the elbow-lever 105 to release its pressure on the bolt 103, which bolt, 120 owing to its spring action, will return to its normal position. When the carriage F makes its inward movement to bring the needle in position to receive a strand, the lug 109 simply passes by the dog 108, as the lower portion of the dog will leave the link 107, and consequently the carriage F will at such time have no controlling action on the clamping-bolt 103. 125

In Fig. 16 I have shown a slight modification in the construction of the improved structure or bed of the machine in which the needle-guide plate G is substituted by a pressure-wheel H' and connected mechanism corre-

sponding in construction and operation to the wheel H, heretofore described. The wheel H' travels at all times below the wheel H, the projections or lugs from one wheel entering the spaces between the projections or lugs of the opposing wheel, and consequently side pieces 69^a are employed in the lower fixed portion of the upper structure of the bed, extending to the upper side pieces 69, and the 5 said side pieces 69^a are provided with slots 70^a, in which the trunnion of the wheel H' travels. The outer terminals 71^a of the said slots 70^a incline downward, or in a contrary direction to the inclination of the terminals 10 71 of the upper slots, and in connection with the lower section of the bed just described a rack 79^a is employed, adapted to be engaged by a gear 80^a, operating a pinion corresponding to the pinion 81 described, which pinion 15 acts upon a gear on the depressing-wheel H' corresponding to the gear 83, also previously described. A second stud or post 76^a is extended downward from the carriage F, to which stud arms or links 75^a are pivoted, 20 which arms or links 75^a carry the depressing-wheel H' and associate gearing.

In operation, supposing the needle 43 to be in the initial position shown in Fig. 3 and the upper section of the bed or upper structure being raised or in normal position, the 25 openly-woven cane fabric K, with warp and weft strands woven upon any suitable machine, is passed diagonally over the base between the sections of the bed or upper structure C, the said fabric being wound upon one reel supported upon the base and is adapted for attachment to the opposing reel as the diagonal strands are passed through the fabric. In placing the cane fabric adapted to receive the 30 diagonal strands the projections 62 on the needle-guide G and the projections 58 from the standards 57, attached to the brackets D and D', are made to enter the openings in the fabric K, and then the treadle 84 is pressed 35 down, closing the upper section of the upper structure or bed-section C upon the lower section. Power is now applied to the cross-head 44 of the carriage F and the needle 43 is started upon its forward movement, the guides 40 45 50 55 60 65 70 75 80 85 90 95 100 105 110 115 120 125 130 135 140 fabric, depressing the warp-strands at each side of the weft-strands, and a needle adapted to carry the strand to be diagonally placed, which needle moves concertedly with the depressing device, passing over the depressed warp-strands and under adjacent weft-strands, as set forth.

2. In a machine for inserting diagonal strands in woven-cane fabric, a rotary depressing device adapted to travel over the fabric and depress the strands running in one direction at each side of the strands running at an angle to the first-named strands, and a needle adapted to carry the diagonal strand, moving concertedly with the depressing device in the path in the fabric made by the depressing device, as specified.

3. In a machine for inserting diagonal strands in woven-cane fabric, a rotary depressing device adapted to travel over the fabric and depress the strands running in one direction at each side of the strands running at an angle to the first-named strands, a needle adapted to carry the diagonal strand, moving concertedly with the depressing device in the path in the fabric made by the depressing device, a threading device for the needle at one end of its stroke, and means for disconnecting the strand from the needle at the opposite end of the stroke, as described.

4. In a machine for inserting diagonal strands in woven-cane fabric, a rotary depressing device adapted to travel over the fabric to depress the strands running in one direction, at each side of the crossing strands, a needle adapted to carry the diagonal strand, moving concertedly with the depressing device in the path made by the said depressing device, a carriage for actuating the depressing device, and a holder for the needle having movement in said carriage, whereby the eye of the needle takes a position centrally with respect to the depressing device in the movement of the two in one direction, and a position in advance of the depressing device in the movement of the two in the opposite direction, as set forth.

5. In a machine for inserting diagonal strands in woven-cane fabric, a rotary depressing device adapted to travel over the fabric to depress the strands running in one direction at each side of the crossing strands, a needle adapted to carry the diagonal strand, moving concertedly with the depressing device in the path made by the said depressing device, a carriage for actuating the depressing device, a holder for the needle having movement in said carriage, whereby the eye of the needle takes a position centrally with respect to the depressing device in the movement of the two in one direction, and a position in advance of the depressing device in the movement of the two in the opposite direction, a threading device for the needle at one end of its throw, and means for freeing the needle, located adjacent to the opposite end of its throw, as set forth.

6. In a machine for inserting diagonal strands in woven-cane fabric, a depressing-wheel provided with transversely-opposing lugs at its peripheral surface adjacent to its side edges, whereby central and transverse channels are formed at the periphery of the wheel, and a co-operating track-surface for the said wheel, between which two parts the woven-cane fabric is received and operated upon, as set forth.

7. In a machine for inserting diagonal strands in woven-cane fabric, a bed comprising a lower fixed section and an upper section movable to and from the fixed section, a needle-guide bar permanently attached in the lower section of the bed and provided with a central longitudinal channel and channels diagonally crossing the central channel, and a depressing-wheel mounted to travel in the upper section of the bed over the said bar, the said depressing-wheel being provided with transversely-opposing longitudinal lugs adapted to enter the diagonal channels in the said bar and forming a central peripheral channel which registers with the central longitudinal channel of the bar, for the purpose set forth.

8. In a machine for inserting diagonal strands in woven-cane fabric, a bed comprising a lower fixed section and an upper section movable to and from the fixed section, a needle-guide bar permanently attached in the lower section of the bed and provided with a central longitudinal channel and channels diagonally crossing the central channel, a depressing-wheel mounted to travel in the upper section of the bed over the said bar, the said depressing-wheel being provided with transversely-opposing peripheral lugs adapted to enter the diagonal channels in the said bar, and forming a central peripheral channel which registers with the central longitudinal channel of the bar, a needle adapted to carry the diagonal strand and travel partially in the central channel of the bar and the central peripheral channel of the depressing-wheel, and means, substantially as described, for moving the said needle concertedly with the said depressing-wheel, as and for the purpose described.

9. In a machine for inserting diagonal strands in woven-cane fabrics, a bed consisting of a lower fixed section and an upper section movable to and from the fixed section, a needle-guide bar secured in the lower section, provided with a longitudinal channel and with diagonal channels crossing the longitudinal channel, and a series of pins extending from the bar between the diagonal channels, guide-plates carried by the upper section of the bed, having apertures to receive the projections or pins on the needle-guide bar, a depressing-wheel mounted to turn and having sliding movement in the upper section of the bed, the said depressing-wheel being provided with peripheral lugs arranged in transverse pairs, adapted to en-

- ter the diagonal recesses of the bar, whereby a central peripheral channel is formed at the periphery of the wheel which registers with the longitudinal channel in the said needle-
5 guide bar, a needle-holder adapted for horizontal movement, and a needle in the said holder, adapted to travel partially in the longitudinal channel of the bar and in the peripheral channel of the depressing-wheel, as
10 described.
10. In a machine for inserting diagonal strands in woven-cane fabrics, a bed consisting of a lower fixed section and an upper section movable to and from the fixed section, a
15 needle-guide bar secured in the lower section, provided with a longitudinal channel and with diagonal channels crossing the longitudinal channel, and a series of pins extending from the bar between the diagonal
20 channels, guide-plates carried by the upper section of the bed, having apertures to receive the projections or pins on the needle-guide bar, a depressing-wheel mounted to turn and have sliding movement in the upper section of the bed, the said depressing-wheel being provided with peripheral lugs arranged in transverse pairs adapted to enter the diagonal recesses of the bar, whereby a central peripheral channel is formed at the
25 periphery of the wheel which registers with the longitudinal channel in the said needle-guide bar, extensions from the end of the lower section of the bed, a carriage mounted to travel upon the said extensions, a needle-
30 holder having movement in the said carriage, means for operating the said needle-holder to impart movement thereto and movement to the carriage, and a needle secured in the said holder, which needle is adapted to carry
35 the diagonal strand and to travel partially in the longitudinal channel in the needle-guide bar and partially in the peripheral groove of the depressing-wheel, for the purpose described.
- 40 11. In a machine for inserting diagonal strands in woven-cane fabrics, a bed consisting of a lower fixed section and an upper section movable to and from the fixed section, a needle-guide bar secured in the lower section,
45 provided with a longitudinal channel and with diagonal channels crossing the longitudinal channel, and a series of pins extending from the bar between the diagonal channels, guide-plates carried by the upper section of
50 the bed, having apertures to receive the projections or pins on the needle-guide bar, a depressing-wheel mounted to turn and have sliding movement in the upper section of the bed, the said depressing-wheel being provided with peripheral lugs arranged in trans-
55 verse pairs adapted to enter the diagonal recesses of the bar, whereby a central peripheral channel is formed at the periphery of the wheel, which registers with the longitudinal channel in the said needle-guide bar, extensions from the end of the lower section of the bed, a carriage mounted to travel upon the

60 said extensions, a needle-holder having movement in the said carriage, means for operating the said needle-holder to impart movement thereto and movement to the carriage, a needle secured in the said holder, which needle is adapted to carry a diagonal strand and to travel partially in the longitudinal channel in the needle-guide bar and partially in the peripheral groove of the depressing-wheel, a needle-threading device at one end of the throw of the said needle, and a releasing device for the needle at the opposite end of its throw, substantially as described. 80

65 12. In a machine for inserting diagonal strands in woven-cane fabrics, the combination with a bed, a needle-guide bar carried by the bed having diagonal and longitudinal channels produced therein, a section of the bed being movable to and from the section carrying the said needle-guide bar, and a depressing-wheel held to turn and slide in the movable section of the bed, having transversely-alining lugs therein to enter the diagonal channels in the needle-guide bar, the circumferential space between the lugs registering with the longitudinal space in the needle-guide bar, of tracks projected from the fixed section of the bed, a carriage held 95 to travel on the said tracks, a needle-holder mounted to slide in the said carriage, a needle secured in the said holder, adapted to receive and carry a diagonal strand, a wall of the eye of the needle being sharpened, an actuating device for the needle-holder; an actuating connection between the carriage and the support for the depressing-wheel, an anvil located at the relieving end of the needle-guide bar, a spring-controlled bolt carried by the fixed section of the bed and located opposite the said anvil, and means substantially as described for operating the said bolt by the movement of the carriage, as described. 100

70 13. In a machine for inserting diagonal strands in woven-cane fabric, the combination with a fixed support, a needle-guide bar carried by the said support, track extensions from one end of the said support, an anvil at 115 one end of the needle-guide bar, and a spring-controlled bolt carried by the support and having movement to and from the said anvil, of a carriage mounted to travel on the said tracks, a needle-holder mounted on the carriage, a needle in the said holder, adapted to travel over the needle-guide bar between the anvil and the bolt and to carry a diagonal strand, a lug projected from the carriage, a bar extending at one side of one of the tracks, 120 a link pivotally connected with the bar and with the track adjacent to which it is located, a dog pivoted on the said link and adapted to be engaged by the projection from the said carriage, and a lever operated by the said bar 125 and adapted to operate on the said bolt to force the bolt in direction of the said anvil, as described. 130

75 14. In a machine for inserting diagonal

strands in woven-cane fabric, a support provided with a slot therein, a needle the point of which is held to reciprocate over the said slot, a buffer for the point of the needle carried by the said support, a fixed inclined guide located above the said slot, a spring-controlled pawl pivoted in diagonal relation to the said guide, a strand of material being adapted to be passed between the guide and 10 pawl and when so placed directed through the eye of the needle over the slot in the support, a stirrup carried by the said support for limiting the downward movement of the strand, and a spring carried by the support 15 and extending out at one end into the slot of the support to sustain the said strand in a horizontal position, as described.

15. In a machine for inserting diagonal strands in woven-cane fabric, a depressing 20 device for the cane, consisting of a wheel provided with a series of transversely-opposing lugs at its peripheral surface, whereby central and transverse channels are formed at the periphery of the wheel, the central channel being adapted to receive the diagonal 25

strand to be inserted and the transverse channels being adapted to accommodate the woven strands of the fabric into which the diagonal strand is to be introduced, while the projections on the wheel act to depress the 30 warp-strands of the woven fabric at each side of the weft-strands, as described.

16. In a machine for inserting diagonal strands in woven-cane fabric, a rotary depressing device adapted to travel over the 35 fabric, depressing the strands leading in one direction at each side of the crossing strands, and a needle adapted to carry a strand to be diagonally placed, which needle has movement concertedly with the depressing device, 40 passing over the depressed strands and under adjacent crossing strands.

In testimony whereof I have signed my name to this specification in the presence of two subscribing witnesses.

LOUIS JANSON.
